United States Patent Office

Des. 206,265
Patented Nov. 22, 1966

206,265

DRAPERY TRAVERSE TRACK OR SIMILAR ARTICLE

Gerald T. Shea, 29 Dartmouth, Deer Park,
Long Island, N.Y. 11100

Filed May 20, 1965, Ser. No. 85,383

Term of patent 14 years

(Cl. D21—1)

FIG. 2

FIG. 1

FIG. 1 is a front elevational view of a drapery traverse track or similar article, showing my new design; and

FIG. 2 is an end elevational view thereof.

I claim:

The ornamental design for a drapery traverse track or similar article, as shown.
